CLAIM

The ornamental design for a bulbous grip for a writing instrument, as shown and described.

DESCRIPTION

FIG. 1 is a front perspective view of a bulbous grip for a writing instrument of the design;

FIG. 2 is a side elevational view thereof;

FIG. 3 is a front elevational view thereof;

FIG. 4 is a rear elevational view thereof;

FIG. 5 is a bottom plan view thereof; and,

FIG. 6 is a top plan view thereof.

The portions of the writing instrument depicted by means of broken lines have been shown for illustrative purposes only and form no part of the claimed design.
